(57) **CLAIM**

The ornamental design for a housing for a battery charger, as shown and described.

DESCRIPTION

FIG. 1 is a left side perspective view of a housing for a battery charger showing our new design;

FIG. 2 is a right side perspective view thereof;

FIG. 3 is a left side view thereof;

FIG. 4 is a right side view thereof;

FIG. 5 is a front view thereof;

FIG. 6 is a rear view thereof;

FIG. 7 is a top view thereof; and,

FIG. 8 is a bottom view thereof.

The broken line bounded regions and unshaded regions are for illustrative purposes and form no part of the claimed design. The unshown portion of the design forms no part of the claimed design.
